UNITED STATES PATENT OFFICE

136,401

DESIGN FOR A FINGER RING

Abraham Sager, Chicago, Ill.

Application July 19, 1943, Serial No. 110,680

Term of patent 3½ years

To all whom it may concern:

Be it known that I, Abraham Sager, a citizen of the United States and resident of Chicago, in the county of Cook and State of Illinois, have invented a new, original, and ornamental Design for a Finger Ring, of which the following is a specification, reference being had to the accompanying drawing, forming a part thereof.

In the drawing, Figure 1 is a perspective view of a finger ring showing my new design; and Figure 2 is an enlarged fragmentary plan view showing the design details.

The ornamentation shown extends throughout the entire circumference of the ring.

I claim:

The ornamental design for a finger ring, as shown and described.

ABRAHAM SAGER.
